G. JARBOE

SHEARS SHARPENER

Filed April 9, 1927

Patented Sept. 18, 1928.

1,684,866

UNITED STATES PATENT OFFICE.

GRANT JARBOE, OF FINDLAY, OHIO.

SHEARS SHARPENER.

Application filed April 9, 1927. Serial No. 182,405.

The present invention relates to an improved product of manufacture which is such in construction as to permit it to be conveniently defined as a shears sharpener, 5 that is, an implement whose construction is such as to permit it to be employed as an aid in sharpening scissors blades, shears blades, and similar cutting instruments such as are employed more exclusively in barber 10 shops.

Broadly the improved device comprises a clamp or vise in which the blade to be sharpened is firmly held, together with a roller guide to accommodate and aid manipulation of the abrasive tool for files or other 15 instrument employed in sharpening the cutting edge of said blades.

A distinguishing feature of the vise is a wooden body which it includes which 20 operates with the cutting blade and the clamping plate to minimize objectionable metallic vibrations and noises during the sharpening operation.

Another and indispensable feature is a 25 roller carrying plate which is adjustably mounted on the vise in a position to permit it to conveniently accommodate the reciprocatory strokes of the file.

Other features and advantages flowing 30 from the seemingly new organization of parts will become more readily apparent from the subsequent description and accompanying drawings.

In the drawings:

Figure 1 is an end view of the improved 35 structure.

Figure 2 is a top plan view thereof,

Figure 3 is an enlarged fragmentary inside 40 elevational view.

In the drawings, the reference character 1 designates generally the improved vise. This is shown supported on an appropriate base 2. It comprises an elongated block of wood 3 on one side of which is a metallic 45 clamping plate 4. This plate is adjustably mounted on bolts 5 passing transversely through the wooden block and anchored therein in any suitable manner. The screw threaded ends of these bolts project through 50 and beyond openings in a clamping plate and carry washers 6 and retaining nuts 7, the nut being preferably of wing type. In practice, the blade to be sharpened is clamped firmly between the plate 4 and the 55 block of wood. As before stated, the block of wood is particularly important in that it

substantially eliminates the metallic clinking noise and permits a more dependable clamping action to be had.

Disposed against the opposite flat face of this wooden body is another plate 8 having elongated slots 9 formed therein. This plate is held in place by bolts 10 provided with washers 11 and retaining nuts 12. The threaded ends of the bolts project 60 through and beyond the elongated slots and this arrangement permits the plate to be adjusted vertically with respect to the base 2. Observing the upper end portions of the plate 8 it will be noted that these are provided with right angularly disposed flanges 13 having their upper end portions projecting above the top of the block. These projecting portions are formed with openings 70 providing bearings for reception of a retaining bolt 14 for a file rest roller 15 which is located between the upstanding portions of said flanges. Incidentally, it will be noted that the adjacent edge or corner portion of the wooden block is cut away as at 75 16 to provide clearance to permit free rotation of the roller.

In practice, the blade to be sharpened is clamped between the jaws of the vise, these jaws being formed by the parts 3 and 4 already described. The pointed end of the blade is preferably arranged on the right hand end of the device. Then the roller carrying plate 8 is adjusted to the desired height as the file or other sharpening medium is reciprocated across the roller 15 and engaged with the cutting edge of the blade 80 in an obvious manner.

It is thought that by considering the foregoing description in connection with the 85 drawings, a clear understanding of the construction and arrangement of parts as well as the method of use and advantages will be quite clear. In view of this, a more lengthy description is thought unnecessary.

Minor changes coming within the field of invention claimed may be resorted to if desired.

I claim:

1. As a new product of manufacture, a 105 blade clamping device comprising a wooden backing block, a metal clamping plate and retaining means for said plate, together with an adjustably mounted roller supported on said block adjacent the top of the 110 latter.

2. As a new product of manufacture, a

blade clamping vise comprising a backing block, bolts carried thereby, a clamping plate associated with one side of the block, retaining nuts for said plate, the opposite 5 side of the block being cut away at its top to provide a clearance space, a roller mounted for rotation in said clearance space, and a support for said roller comprising a plate adjustably mounted on the last named side 10 of said block.

3. In a sharpener of the class described, a backing member of compressible material, blade clamping means on one side of the body and means on the opposite side of the

body for aiding in the manipulation of a 15 sharpening implement comprising an adjustably mounted plate, and a rest roller carried thereby.

4. As a new product of manufacture, a 20 base, a blade clamping vise supported thereon and comprising a wooden backing block, blade clamping means on one side of the block, a file rest and manipulating roller on the opposite side of the block, and means for adjustably mounting said roller on said 25 block.

In testimony whereof I affix my signature.

GRANT JARBOE.
